(57) **CLAIM**

The ornamental design for a hair dryer, as shown and described.

DESCRIPTION

FIG. 1 is a front and top perspective view of a first embodiment of a hair dryer showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a rear and bottom perspective view thereof.

FIG. 9 is an exploded view thereof.

FIG. 10 is an enlarged view of a first embodiment of a hair dryer, taken from the circle part in FIG. 1.

FIG. 11 is a front and top perspective view of a second embodiment of a hair dryer showing my new design.

FIG. 12 is a front view thereof.

FIG. 13 is a rear view thereof.

FIG. 14 is a left side view thereof.

FIG. 15 is a right side view thereof.

FIG. 16 is a top view thereof.

FIG. 17 is a bottom view thereof.

FIG. 18 is a rear and bottom perspective view thereof.

FIG. 19 is an exploded view thereof; and,

FIG. 20 is an enlarged view of a second embodiment of a hair dryer, taken from the circle part in FIG. 11.

The broken lines in the drawings depict portions of the hair dryer that form no part of the claimed design.
